(57) **CLAIM**

The ornamental design for a mount for game controllers, as shown and described.

DESCRIPTION

FIG. 1 is a left side view of a mount for game controllers, showing the new design;

FIG. 2 is a left side perspective view thereof;

FIG. 3 is a right side view thereof;

FIG. 4 is a right side perspective view thereof;

FIG. 5 is a top view thereof;

FIG. 6 is a bottom view thereof;

FIG. 7 is a front view thereof;

FIG. 8 is a front perspective view thereof;

FIG. 9 is a rear view thereof; and,

FIG. 10 is a rear perspective view thereof.

The broken lines in the drawing depict unclaimed portions of the mount for game controllers and form no part of the claimed design.
